UNITED STATES PATENT OFFICE.

ALLAN B. FIELD, OF NORWOOD, OHIO, ASSIGNOR TO ALLIS CHALMERS COMPANY, A CORPORATION OF NEW JERSEY, AND THE BULLOCK ELECTRIC MANUFACTURING COMPANY, A CORPORATION OF OHIO.

DYNAMO-ELECTRIC MACHINE.

No. 899,447.

Specification of Letters Patent.

Patented Sept. 22, 1908.

Application filed November 30, 1906. Serial No. 345,602.

To all whom it may concern:

Be it known that I, ALLAN B. FIELD, citizen of the United States, residing at Norwood, in the county of Hamilton and State of Ohio, have invented certain new and useful Improvements in Dynamo-Electric Machines, of which the following is a full, clear, and exact specification.

My invention relates to dynamo-electric machines and particularly to anti-hunting or damping devices or to means for preventing irregularity of movement or hunting of such machines as alternating current generators, synchronous motors, rotary converters, etc.

The object of my invention is to provide an anti-hunting device which is very effective in operation, simple in construction and so located as not to detract from the appearance of the machine or to add materially to its weight.

My invention consists in certain novel details of construction and combinations of elements described in the specification and set forth in the appended claims.

The anti-hunting device may be applied to stationary or rotary members. In this particular case it is shown in connection with rotary field poles.

For a better understanding of my invention reference is had to the accompanying drawings in which

Figure 1 is an elevation of a portion of a rotary field member equipped with my invention; Fig. 2 is a section through one of the poles, the plane of the section being parallel to the plane of rotation; Fig. 3 is a section through one of the poles at right angles to the plane of rotation; Fig. 4 is a view of one of the anti-hunting or damping devices removed from the pole; Figs. 5 and 6 are sectional views through a pole equipped with a modified form of my invention, the views being similar to Figs. 2 and 3 respectively.

Referring now to the figures of the drawings, I have shown at 10 a portion of a rotary field member including a portion of a spider 11 and two field magnets 12 each of which is equipped with my improved damping or anti-hunting device. Each field pole is built up of laminæ clamped between end-plates 13 by rivets 14. Each pole is provided with a field coil 15 consisting of a number of turns of edge-wise wound copper, which rests

on a wooden coil seat 16 surrounding the pole 55 at its base, and is prevented from slipping off the outer end of the pole by pole tips 17 of the laminæ and a projecting ledge 18 of each end-plate.

Surrounding the outer end of each pole and bearing against the pole tips 17 and the ledges 18 of the end-plates is a collar or ring 19 of good current conducting material, preferably of copper, which ring forms a part of the damping or anti-hunting device. As is 65 shown in Fig. 4 the ring is provided with inwardly extending lugs 20 which bear against the sides of the pole. Intermediate the copper ring and the outermost layer of the coil is an insulating ring 26. In addition to the 70 ring acting as a damper it serves to support the coil.

Extending through the outer end of each pole close to the pole face and at right angles to the plane of rotation of the rotary member are a plurality of bars 21 of copper or other good conducting material, in this case two in number. These bars with the copper ring 19 compose the damping device of each pole. As is shown the rods pass through 80 aligned openings 22 and 23 in the laminæ and end plates respectively and are secured to the copper rings by screws 24. In Figs. 2 and 3 the openings in the laminæ form partially open slots in the pole face so that the 85 rods are not entirely surrounded by the iron of the laminæ. The openings in the end-plates are made slightly larger than the rods, and after the rods are secured together type-metal or other easily fusible metal is poured 90 into the openings so as to obtain a firm and compact structure. This filling metal is shown at 25. As shown in Figs. 2 and 3 the copper rods are surrounded by insulation. This is not necessary however, and may be 95 omitted if desired. The damping bars 21 are preferably so arranged as to divide the pole face into sections which are whole multiples of the stator slot pitch, particularly if open stator slots are employed. The sections need not be equal in length and are shown unequal in the drawings. The purpose of this is to insure a uniform area of stator iron in line with each section at all times so that the flux passing through each 100 section of the pole face will be constant. Otherwise heavy currents would be generated in the dampers tending to maintain the

flux constant when no hunting was taking place.

In Figs. 5 and 6 the construction is substantially the same. In this case however the alined openings 22^a in the laminea do not form open slots in the pole face, and the recesses 23^a in the end-plates to receive the ends of the bars do not extend entirely through said plates, so that after the coil is 10 in place on the pole, said bars 21^a are completely hidden. The bars are secured to the rings 19^a by screws as in the case first described, and the excess spaces in the end-plates are also filled with metal, such as type 15 metal.

When the machine is in operation, the ring and bars, shown best in Fig. 4 form the seat of induced currents which prevent in a great measure irregularities in speed above 20 and below synchronism. Damping or anti-hunting devices are so well known that further explanation of the theory of operation is deemed unnecessary.

It will be seen that by my improved damping or anti-hunting device is very light in 25 weight, simple in construction and easy to manufacture and assemble in the pole. Its construction and arrangement and location in the pole are such as to render it most effective. Furthermore the rods being embedded in the pole, it does not mar the appearance of 30 a machine to which it is applied as have other damping devices, which heretofore have been more or less cumbersome and 35 bulky.

I do not wish to be confined to the exact details shown but aim in my claims to cover all modifications which come within the spirit and scope of my invention.

40 What I claim as new and desire to secure by Letters Patent is:—

1. In a dynamo-electric machine, a field pole made up of laminea and end plates, and a damping or anti-hunting device therefor, 45 comprising a low resistance ring independent

of said laminea and end plates and surrounding the pole, and one or more separable bars or rods of low resistance embedded in said laminea at right angles thereto and projecting into recesses in said end plates and engaging 50 the ring.

2. In a dynamo-electric machine, a field magnet comprising a pole provided with lateral coil-retaining projecting portions at its outer end and a field coil surrounding said 55 pole, and a damping or anti-hunting device therefor comprising a low resistance ring surrounding said pole and located between the coil and the coil - retaining projecting portions of the pole, a plurality of independent 60 bars or rods of low resistance embedded in the pole face and having their ends extending into said coil-retaining projecting portions adjacent to the ring, and means for fastening the extending ends of said bars or 65 rods to said ring at opposite sides of the pole.

3. In a dynamo-electric machine, a field magnet comprising a pole - piece and field coil, said pole-piece being made up of a plurality of laminations and end-plates, a plurality of bars of good conducting material embedded in the pole face and projecting beyond the laminations, the end-plates being at their outer ends provided with coil-retaining projecting portions recessed to receive 75 the projecting ends of said bars, a ring of good conducting material surrounding said pole-piece between the coil and the projecting portions of the end-plates, and means for fastening the ring to the ends of said bars, 80 the whole being so constructed that when the pole-piece and coil are assembled the bars are not visible from the exterior.

In testimony whereof I affix my signature, in the presence of two witnesses.

ALLAN B. FIELD.
